LOOSE MATCH HOLDER

Harry Walters, Kansas City, Mo.

Application November 11, 1935, Serial No. 49,152

6 Claims. (Cl. 206—29)

This invention relates to loose match holders of the type which may be formed of a single strip of sheet material after it has been printed or otherwise decorated in a flat condition, and the primary object of the invention is to provide such an article of manufacture having as salient features thereof, a novelly formed pocket with two entrances through which may project two distinct rows of matches, and a novelly formed, integral cover that may be moved to and from a position over the projected ends of the matches held in the pocket.

Another important aim of this invention is to provide a loose match holder which may be made without the use of special machinery and by one unskilled in the art of manufacturing so-called "book-type" matches.

A still further object of the invention is the provision of a match holder of the aforementioned character that may be used over and over again merely by refilling the same after the initial filling of matches has been exhausted.

Other objects of the invention, including specific structural details of the holder per se and the novel manner in which the rows of matches are held so as to present a pleasing appearance and compact package, will appear during the course of the following specification, referring to the accompanying drawing, wherein:

Figure 1 is a perspective view of a loose match holder embodying the present invention.

Fig. 2 is a face view of the match holder in the opened condition.

Figs. 3 and 4 are transverse cross sections taken on lines III—III and IV—IV respectively of Fig. 2, and,

Fig. 5 is a vertical, longitudinal, central section through the closed loose match holder.

The holder itself may be formed of a strip of sheet material such as cardboard, pasteboard, heavy paper, or other substance which will bend and that will be economical and have the characteristics of taking ink for the purpose of printing thereon desirable advertising. After the strip is printed and formed into the holder by being bent along two parallel lines intermediate the ends thereof, there is created a bight 8 and a bight 10 that are in parallel relation with the body portion 12 therebetween. The rebent part 14 between one end of the strip and bight 10 is secured in place by a pair of wire stitchings 16, one of which is at each side of the rebent portion 14 and, preferably, in parallel relation with the coinciding edges of portions 12 and 14.

A pocket 20 is created between rebent portion

14 and body portion 12, which has an open top formed along the edge 22 of the rebent strip. A slot 24 is formed through the rebent portion 14 intermediate bight 10 and edge 22 and in parallel relation with the same. This slot 24 extends but part way across portion 14 and an ear 26 is formed at each end respectively of slot 24 by slitting portion 14 outwardly from slot 24, as illustrated in Fig. 2. These slits 28 permit angling of the ears 26 inwardly out of the plane of the material at the ends of slot 24 so that matches 30 at the end of a row thereof which projects through slot 24 may be engaged. Such construction will eliminate a bind at this point which normally creates destruction by tearing the material so that the slot will no longer hold the row of matches 30 in a desirable manner.

Another row of matches enters pocket 20 through the open top thereof and the stick ends of matches 30 are all confined together at the bottom of pocket 20 in a manner seen in Fig. 5. The heads of matches 30 in both rows lie in a common plane extending transversely through the holder and each row of matches 30 assumes a fan shaped character, as illustrated in Fig. 2.

The cover portion 32 of the holder is between one of the lines of fold which forms bight 8 and end 34 of the strip. When cover 32 is moved to the closed position, it will overlie all of the matches projecting from pocket 20 and overlap a part of the area of portion 14.

An ear 36 extends outwardly from end 34 of cover 32 and another slot 38, formed in rebent portion 14, receives ear 36 for the purpose of releasably securing the cover in place. This slot 38 is very similar to slot 24 and is parallel therewith and between slot 24 and bight 10. When ear 36 enters slot 38, it fits snugly against matches 30 and when the supply of matches is insufficient to present such snug fit, the length of ear 36 is such that it will not be accidentally withdrawn from slot 38.

A strip of abrasive substance 40 should be provided on the outer face of portion 14 below cover 32 so that when a match 30 is withdrawn and cover 32 is closed, the match may be struck by drawing the head thereof across abrasive 40.

The advantages of this invention are numerous. A number of them have become apparent through the specification, and while one specific form of the invention is exemplified in the drawing, it is desired to be limited only by the scope of the appended claims.

Having thus described the invention, what is

claimed as new and desired to be secured by Letters Patent is:

1. A loose match holder comprising a single strip of sheet material rebent upon itself near one end to form an open top pocket; securing means for holding the rebent portion of the strip in place; a slot formed through the rebent portion of the strip, intermediate the bight and inturned end of the strip and parallel thereto; and two rows of matches having their stick ends within the pocket, one row of matches extending outwardly from the pocket through the said slot and the other row of matches extending from the pocket between the inturned end of the strip and the intermediate portion of the strip.

2. A loose match holder comprising a single strip of sheet material rebent upon itself near one end to form an open top pocket; securing means for holding the rebent portion of the strip in place; a slot formed through the rebent portion of the strip, intermediate the bight and inturned end of the strip and parallel thereto; and two rows of matches having their stick ends within the pocket, one row of matches extending outwardly from the pocket through the said slot and the other row of matches extending from the pocket between the inturned end of the strip and the intermediate portion of the strip, said two rows of matches having their heads in a common plane extending transversely through the strip.

3. A loose match holder comprising a single strip of sheet material rebent upon itself near one end to form an open top pocket; securing means for holding the rebent portion of the strip in place; a slot formed through the rebent portion of the strip, intermediate the bight and inturned end of the strip and parallel thereto; and two rows of matches having their stick ends within the pocket, one row of matches extending outwardly from the pocket through the said slot and the other row of matches extending from the pocket between the inturned end of the strip and the intermediate portion of the strip, the matches in the said two rows being inclined with respect to the perpendicular to the said inturned end and said slot to present fan-shaped rows having their widest dimensions across the projected, head ends of the rows of matches.

4. A loose match holder comprising a single strip of sheet material rebent upon itself near one end to form an open top pocket; securing means for holding the rebent portion of the strip in place; a slot formed through the rebent portion of the strip, intermediate the bight and inturned end of the strip and parallel thereto; and two rows of matches having their stick ends within the pocket, one row of matches extending outwardly from the pocket through the said slot and the other row of matches extending from the

pocket between the inturned end of the strip and the intermediate portion of the strip, said two rows of matches having their heads in a common plane extending transversely through the strip, the matches in the said two rows being inclined with respect to the perpendicular to the said in-turned end and said slot to present fan-shaped rows having their widest dimensions across the projected, head ends of the rows of matches.

5. A loose match holder comprising a single strip of sheet material rebent upon itself near one end to form an open top pocket; securing means for holding the rebent portion of the strip in place; a slot formed through the rebent portion of the strip, intermediate the bight and in-turned end of the strip and parallel thereto; two rows of matches having their stick ends within the pocket, one row of matches extending outwardly from the pocket through the said slot and the other row of matches extending from the pocket between the inturned end of the strip and the intermediate portion of the strip; another slot formed through the said rebent portion of the strip between the first mentioned slot and the bight; and an outwardly extending ear on the other end adapted to enter the said other slot when the strip is bent along a transverse line of fold adjacent the heads of the rows of matches whereby to form a cover for the said matches extending from the said pocket.

6. A loose match holder comprising a single strip of sheet material rebent upon itself near one end to form an open top pocket; securing means for holding the rebent portion of the strip in place; a slot formed through the rebent portion of the strip, intermediate the bight and inturned end of the strip and parallel thereto; and two rows of matches having their stick ends within the pocket, one row of matches extending outwardly from the pocket through the said slot and the other row of matches extending from the pocket between the inturned end of the strip and the intermediate portion of the strip, said two rows of matches having their heads in a common plane extending transversely through the strip, the matches in the said two rows being inclined with respect to the perpendicular to the said in-turned end and said slot to present fan-shaped rows having their widest dimensions across the projected, head ends of the rows of matches, said strip having an ear at each end respectively of the slot, formed between parallel longitudinally extending slits cut in the strip outwardly from the slot, said ears being angled out of the plane of the strip to engage the sides of the adjacent matches of the row thereof extending through said slot.

HARRY WALTERS.
